UNITED STATES PATENT OFFICE.

BEATRICE R. STRAHL, OF BROOKLYN, NEW YORK.

FINGER-TIP-TAPERING DEVICE.

1,404,906.

Specification of Letters Patent. Patented Jan. 31, 1922.

Application filed March 9, 1921. Serial No. 450,946.

To all whom it may concern:

Be it known that I, BEATRICE R. STRAHL, a citizen of the United States of America, residing at Brooklyn, in the county of Kings 5 and State of New York, have invented certain new and useful Improvements in Finger-Tip-Tapering Devices, of which the following is a specification.

The present invention relates to devices 10 for tapering finger tips and has for its object to provide a simple construction which will have a lasting effect and which can be worn without any danger of injuring the fingers.

15 With this object in view my invention consists of a longitudinally tapered split tube of substantially oval or egg-shaped cross section of hard springy material as celluloid or the like, which on its inner face 20 is provided with lateral cushions adapted when the tube is applied to the finger tip to press against the fleshy parts of the latter and thereby shape it into tapered form.

25 This invention also consists in the construction of the cushions and the means for the attachment thereof to the tubular body.

It also consists in the particular combination, construction and arrangement of parts 30 as will be hereinafter more fully described and set forth in the appended claims.

35 My invention will be fully understood by reference to the accompanying drawing in which similar characters denote corresponding parts and in which Fig. 1 is a side elevation of the device shown applied to a finger tip; Fig. 2 is a top plan view of said device; Fig. 3 is a longitudinal section on line 3—3 of Fig. 2; Fig. 4 is an end view of the device; 40 Fig. 5 is an enlarged section on line 5—5 of Fig. 1; Fig. 6 is a plan view of the unrolled cushion carrying lining; Fig. 7 is a section on line 7—7 of Fig. 6; Fig. 8 is a section on line 8—8 of Fig. 6; Fig. 9 is a 45 similar view to Fig. 6 of a somewhat modified cushion lining and Fig. 10 is a similar view to Fig. 1 of a modification of the device.

The device substantially consists of a forwardly tapered tubular body 10 of oval or egg-shaped cross section, and of suitable hard but strongly resilient or springy material, such as celluloid or the like. The forward edge 10' of said tubular body is preferably 55 cut at a slant in the downward and rearward direction, so that, while the upper part

of the tube may cover the nail wholly or partly, the fleshy part of the finger tip may be allowed to project beyond the tube to safeguard against possible injury to the 60 wearer when the device is worn and particularly when the wearer is asleep. The rear end 10² of the tube is cut out in the manner shown, whereby sufficient freedom of movement of the finger tip on its joint is 65 obtained.

This device is adapted when shoved over the finger tip to compress the lateral fleshy parts thereof, so as to give it a tapered shape. Inasmuch as the tapering of the finger tip 70 by such device, to have a lasting effect requires a continuous considerable pressure on the fleshy parts of the finger, the wearing of the tube for any length of time may be very uncomfortable and in fact irritate the 75 flesh. To avoid this evil, I found it advantageous to provide inside the tube lateral cushions 11 of suitable soft material, which when the tube is applied will exert the pressure more tenderly on the parts to be 80 treated. In order to prevent soreness and render the flesh more pliable or soft the cushions may be treated with some suitable chemical preparation or substance, such as 85 vaseline or the like.

The cushions 11 may be formed on a pad or lining 12 of soft material which may be cut to conform with the inner shape of the tubular body and which may be suitably attached to the inner face of the tube. 90

I prefer to attach the pad so that it may be conveniently removed. To this end the lining or pad 12 may have a plurality of short strips 13 attached around its margin and preferably formed with beads 14, while 95 the tube 10 may have marginal incisions or recesses 10³ to frictionally or otherwise engage said strips. Or the lining 12' and tube 10 may be formed near their marginal edges with male and female members 16, 17 constituting press buttons or the like. (Figs. 9 and 10.)

100 The cushions 11 may be formed by making the lining of two separate pieces 12^a, 12^b of porous and soft material placed on top of and attached to one another so as to form pockets 12^c which are adapted to receive paddings 11' of cotton or the like, either plain or treated with an appropriate chemical preparation or substance which will tend 110 to soften the flesh to be compressed.

Various modifications may, of course, be

designed in the construction of the device without departing from the principle of my invention. I, therefore, do not wish to limit myself to the details described and shown except as defined in the following claims.

What I claim and desire to secure by Letters Patent is:—

- 10 1. A finger tip tapering device, consisting of a resilient tubular body and cushions removably attached to the inner face of said body and adapted when the device is applied to exert pressure on the finger tip.
- 15 2. A finger tip tapering device, consisting of a split resilient tube and a lining formed with cushions on the inner face of said tube.
- 20 3. A finger tip tapering device, consisting of a split tube of oval cross section and of resilient material.
- 25 4. A finger tip tapering device, consisting of a tube of hard but resilient material split longitudinally at its bottom, and of oval cross section, the rear edge of said tube being cut out in the downward and forward

direction to permit freedom of movement of the finger tip.

5. A finger tip tapering device, consisting of a tubular body of resilient material and an inner lining removably attached to 30 said body and formed with lateral cushions.

6. A finger tip tapering device, consisting of a tubular body of resilient material split longitudinally at its bottom, an inner lining formed with cushions for the fleshy part of 35 the finger tip and means for the removable attachment of said lining to said tubular body.

7. A finger tip tapering device, consisting of a resilient tubular body split longitudinally at its bottom, and cushions on the inner face of said body serving to exert pressure on the finger tip, said cushions containing flesh softening substance. 40 45

In testimony whereof I affix my signature in presence of two witnesses.

BEATRICE R. STRAHL.
